Inventor:

Harold A. Soulis

UNITED STATES PATENT OFFICE

HAROLD A. SOULIS, OF EASTON, PENNSYLVANIA

INTERNAL-COMBUSTION-ENGINE PISTON

Application filed July 30, 1928. Serial No. 296,257.

The invention is an improvement in pistons for internal combustion engines and means for constructing the same whereby the efficiency of internal combustion engines in 5 which my invention is embodied will be materially increased.

The duty of a bi-metallic piston is to perform the duty of a conventional all iron or all aluminum piston in such a manner that 10 it will have none of the inherent disadvantages of pistons made of one metal. In the all aluminum piston the excessive expansion and excessive skirt wear do not permit the engine to perform at its highest efficiency. 15 In the case of the all iron piston with its insufficient heat conduction and its excessive weight the compression ratio and high engine speed are greatly retarded. As the tendency in modern engine design is toward high 20 speed and high compression ratios, it is seen that a piston light in weight with high heat conductivities must be used. A bi-metallic piston with the proper metals cast integrally and located in the piston so that the advantages 25 of each metal can be used when its particular properties will serve to eliminate the disadvantages of a piston made of a single metal, will have none of their disadvantages.

It is the object of my invention to fulfill 30 these exacting requirements by the construction of an internal combustion engine piston having cast within an aluminum internal combustion engine piston particles or pieces of metal, having wearing qualities better than 35 the wearing qualities of aluminum, such as iron particles, also to cast within the skirt a perforated metal or screen to keep the expansion to a minimum and to retain the particles within a confined area of the internal 40 combustion engine piston.

This invention further comprehends a method of producing an internal combustion engine piston whereby the structure may be economically manufactured, the finished 45 product possessing greater strength and durability than pistons of the conventional types. Furthermore, the pistons made by the practicing of my invention will be lighter in weight than the cast iron piston so that the 50 wear of scoring of the cylinder walls result-

ing from their use will be substantially eliminated or reduced to a minimum.

Other objects and advantages of the employment of my invention will become obvious as the description proceeds, and I would have it understood that I reserve unto myself 55 the full range of equivalents in structure and uses, to which I may be entitled under my invention in its broadest aspect.

I shall now proceed to describe my invention with reference to the accompanying drawings, wherein I have illustrated certain preferred embodiments for the purpose of presenting a clear and comprehensive disclosure, it being obvious that my invention is 60 susceptible of taking other forms without departing from the scope and spirit thereof.

Fig. 1 is an elevation, partly in section taken through the wrist pin boss of a practical form of my invention embodying a wire 65 mesh with particles of metal other than aluminum with which the piston proper is made, cast within the internal combustion engine piston.

Fig. 2 is an elevation of the internal combustion piston. 70

Fig. 3 is a plan view looking at the skirt end of the internal combustion engine piston.

Fig. 4 is an elevation in section through B—A Fig. 3 showing the cast-in metal particles without the reinforcing member. 80

Fig. 5 is an elevation in section of a portion of the skirt of the piston taken at A—B showing the embedded particles and the perforated member cast within the lower portion 85 of the piston.

Referring now to the drawings in detail in which like characters of reference are employed to designate similar parts, throughout the several views, 2 indicates an internal combustion engine piston body consisting of a light cast metal such as aluminum or aluminum alloy with a wire mesh reinforcing member 90 3 with bearing inserts or particles 4 cast integrally with the piston proper, after which the surfaces of the piston are machined to form the ring grooves and the bearing surface. 5 shows the wrist pin boss cast integral with the piston proper. 6 shows the 100

piston ring grooves. 7 shows the wrist pin boss reinforcing rib.

It is manifest that in some instances of construction it may be desirable to modify the shape of the perforated member 3 or that the size and shape of the particles 4 are susceptible to modification. It is obvious that when the perforated member 3 is used the particles 4 will be confined to a limited area. Perforated member 3 further serves to keep the internal combustion engine piston from excessive expansion. It is obvious that if the reinforcing member 3 be of a lower coefficient of expansion than the piston skirt or head section it will hold the aluminum or aluminum alloy from expansion due to the heat of combustion while the bearing particles of a metal of better bearing qualities than the piston proper will give long life to the piston.

20 I claim:

1. An internal combustion engine piston comprising a relatively light body of cast metal, a reinforcing member, wrist pin bosses, a zone where packing ring grooves are cut, a plurality of cast-in bearing particles, all of which are permanently united in casting.

2. An internal combustion engine piston comprising a relatively light body of cast metal, wrist pin bosses, a zone where packing ring grooves are cut, cast-in bearing particles all of which are cast integral.

3. An internal combustion engine piston comprising a relatively light body of cast metal, wrist pin bosses, a zone where packing ring grooves are cut, said light body of cast metal being impregnated with a plurality of pieces of an unlike metal.

4. An internal combustion engine piston comprising a relatively light body of cast metal, wrist pin bosses, a zone where packing ring grooves are cut, said light body of cast metal having portions in the locality of the wearing surfaces impregnated with an unlike metal, said relatively light body of cast metal having a cylindrical shaped reinforcing member interposed between the portion of the said impregnated portions of the relatively light body of cast metal and the major or non-impregnated portions, all of said parts being united in casting.

5. An internal combustion engine piston comprising a relatively light body of cast metal, wrist pin bosses, a zone where packing ring grooves are cut, said light body of cast metal having its wearing surfaces impregnated with an unlike metal.

6. An internal combustion engine piston comprising a relatively light body of cast metal impregnated with particles of an unlike metal and a cylinder of a perforated material cast therein.

7. An internal combustion engine piston composed of a light metal alloy, said alloy being impregnated with particles of a wear-resisting metal.

8. An internal combustion engine piston composed of a light metal alloy, said alloy being impregnated adjacent the wearing surfaces with particles of a wear resisting metal.

9. An internal combustion engine piston composed of a light metal alloy impregnated in the zone of the wall of said piston with a multiplicity of small particles of an unlike metal of wear-resisting characteristics, and a perforated metallic cylindrical expansion-resisting member entirely embedded in the walls of said piston, all permanently united in casting.

10. An aluminum alloy piston for internal combustion engines, impregnated in the zone of wearing surfaces with a plurality of fine particles of a wear-resisting ferrous metal, united permanently with said piston in casting.

11. In combination, an aluminum alloy piston for internal combustion engines, a multiplicity of small particles of ferrous metal embedded in the zone of wearing surfaces of said piston, and a cylindrical perforated metallic expansion-resisting member entirely surrounded by the body of said piston, all of which being permanently united in casting.

HAROLD A. SOULIS.
